[57] CLAIM

The ornamental design for a portrait flower, as shown and described.

DESCRIPTION

FIG. 1 is a front elevational view of a portrait flower showing my new design;

FIG. 2 is a left side elevational view thereof;

FIG. 3 is a rear elevational view thereof;

FIG. 4 is a right side elevational view thereof;

FIG. 5 is a top plan view thereof;

FIG. 6 is a bottom plan view thereof;

FIG. 7 is a front elevational view of a second embodiment of FIG. 1, the difference residing in the substitution of a locket for the single portrait, the stem broken away for ease of illustration; and,

FIG. 8 is a front elevational view of FIG. 7, the locket in a closed position.
